UNITED STATES PATENT OFFICE

WILLIAM A. STRONG, JR., OF JOLIET, ILLINOIS, ADMINISTRATOR OF WM. N. MOORE, DECEASED.

IMPROVEMENT IN COOPERS' BARREL-HEATERS.

Specification forming part of Letters Patent No. 171,489, dated December 28, 1875; application filed December 11, 1875.

To all whom it may concern:

Be it known that WILLIAM N. MOORE, deceased, late of Will county, State of Illinois, invented certain Improvements in a Cooper's Barrel-Heater, the construction and operation of which I will proceed to explain, reference being had to the annexed drawing making a part of this specification, in which—

Figure 1 is a perspective view, and Fig. 2 a vertical sectional view through the center.

The nature of the invention consists in so arranging a portable stove that it may be used to heat the staves of a barrel or cask on the inner side, for the purpose of warping and drying them into the proper shape for the hoops.

In the drawings, *a* represents the fire-box of the stove; *B*, the escape-flue into the drum *H*, for distributing the heat. *D* and *E* represent the opening forming the flue to the escape-flue *C*; *G*, ring on which the barrel *I* rests while heating, and the arrows show the direction of the draft and heat as it passes from the fire-box *a* into the drum *H*, and from thence to the escape-flue *C*.

It will be observed that none of the smoke

and flame pass out into the barrel, but only into the large drum *H*, which heats the interior of the barrel all it is necessary to warp the staves into the proper shape for a barrel, and dry out the staves to make them fit to receive the hoops.

The top plate of the stove, having the drum *H* and escape-flue *C*, may be constructed separately, so that it may be applied to the top of any ordinary stove having a flat top plate and escape-flue passing from the top plate, as shown at *B*, thus converting any such ordinary stove into a barrel-heater, as shown.

Having thus described said invention, what I claim as new, and desire to secure by Letters Patent, is as follows:

The combination of the drum *H*, ring *G*, flues *B* *C* *D* *E*, and fire-box *a*, arranged substantially as and for the purposes set forth.

WILLIAM A. STRONG, JR.,
Administrator of the estate of
William N. Moore, deceased.
